LOOPER MECHANISM FOR SEWING MACHINES

Albert H. De Voe, Livingston Manor, N. Y., assignor to The Singer Manufacturing Company, Elizabeth, N. J., a corporation of New Jersey

Application September 29, 1938, Serial No. 232,249

8 Claims. (Cl. 112—200)

This invention relates to looper-actuating mechanism for chain-stitch sewing machines and has for an object to provide a looper-actuating mechanism which is simple in construction, light in weight and operable at ultra high speeds of the order of 9000 stitches per minute.

With the above and other objects in view, as will hereinafter appear, the invention comprises the devices, combinations and arrangements of 10 parts hereinafter set forth and illustrated in the accompanying drawings of a preferred embodiment of the invention, from which the several features of the invention and the advantages attained thereby will be readily understood by 15 those skilled in the art.

According to the preferred embodiment of the invention, the looper is mounted on a looper-carrier which is pivotally connected at one end to a crank-pin working in an inclined cylindrical bearing in the head of a rotary drive-shaft. The axis of the pivotal connection between the looper-carrier and crank-pin is transverse to the longitudinal axis of the crank-pin, so that, as the drive-shaft rotates, the gyroscopic movement imparted by the inclined cylindrical bearing to the 20 crank-pin causes the looper-carrier to partake of racking and bodily endwise movements, giving to the looper its loop-seizing and needle-avoiding movements. The looper-carrier is slidably supported near the position of the looper by a bearing block which, in turn, is supported for universal tilting movements by and relative to a bearing support adjustably mounted on the machine bed. The universally mounted bearing 25 which slidably supports the looper-carrier, permits the latter to spring, snake and whip under the stresses of ultra high speed operation, without cramping any of its bearings.

The invention will be better understood by 30 referring to the accompanying drawing, of which Fig. 1 is a perspective view of the preferred embodiment of the present looper mechanism. Fig. 2 is an end elevation, Fig. 3 a top plan view and Fig. 4 a front elevation of the mechanism. Fig. 45 5 is a disassembled perspective view of the looper-bar and the universally tilttable bearing-support therefor and Fig. 6 is a section on the line 6—6, Fig. 2.

The sewing machine is constructed with a bed 50 1 having a bearing lug 2 in which is mounted the bearing bushing 3 for the rotary drive-shaft 4 having at one end a conical shaft-head 5 which is formed with a hollow cylindrical bearing 6 the longitudinal axis of which is inclined to and co-

planar with the longitudinal axis of the drive-shaft 4.

Journalized in the bearing 6 is the crank-pin 7 having at its free-end a head 8 which is slotted at 9 to receive one end of the looper-carrier bar 10 in which is fixed the transverse pivot-pin 11 journalized in the bearings 12, 12 in the head 8. The looper-bar 10 is formed at its opposite end with a cylindrical portion 13 which is rockably and endwise slidably supported in the bearing 10 block 14 constituting the head of a rock-shaft 15 journalized horizontally in the bearing sleeve 16. The bearing sleeve 16 is carried by the head 17 of a rock-shaft 18 which is journaled vertically in a bearing-supporting block 19 secured by the 35 screw 20 to a block 21 mounted on the bed 1. The blocks 19 and 21 have a rib-and-groove positioning connection 22, Fig. 2, which extends in a direction parallel to the axis of the drive-shaft 4. By loosening the screw 20, the block 19 may be 20 adjusted in a direction parallel to the axis of the drive-shaft 4.

The crank-pin 7 has secured thereto a collar 23 which works in a slot 24 in the conical shaft-head 5. By loosening the collar 23 on the crank-pin 7, the latter may be adjusted lengthwise of the bearing 6 to vary the amplitude of the side- 25 wise motion imparted to the looper 25 which is mounted on the looper-bar 10. The looper 25 cooperates, as usual, with the reciprocating eye-pointed needle 26; the looper advancing at one side of the needle in seizing a needle-loop, then shifting sidewise and returning at the other side of the needle-path, so that the descending needle 30 may enter a loop of the looper-thread in the formation of the conventional two-thread chain-stitch.

By mounting the looper on a slender looper-bar which is light in weight and is supported at one end by a universally tilting bearing and 40 driven at its other end by an inclined crank connection with a rotary shaft, there is produced a mechanism which may be operated at very high speeds. The looper-bar may spring, snake, flex or whip without cramping any of the bearings. 45 This is a desirable attribute of a high speed mechanism.

The invention is not limited to a thread-carrying looper as it is obviously adaptable to drive any sewing machine looper-blade to which loop-seizing and loop-shedding movements are to be 50 imparted. The sidewise or needle-avoiding movements may or may not be had, depending upon the working position of the crank-pin 7 in its bearing 6. If this position is such that the 55

axes of the pivot-pin 11 and shaft 4 intersect, there will be no needle-avoiding movement imparted to the looper.

The provision of the universally tiltable bearing support 14 for the looper-bar 10, in combination with the adjustable crank-pin 7, permits the amplitude of the side motion of the looper 25 to be adjusted by shifting the crank-pin 7 relative to the collar 23 which is releasably secured to it.

Having thus set forth the nature of the invention what I claim herein is:

1. In looper mechanism for sewing machines, the combination with a rotary shaft and shaft-head formed with a hollow cylindrical bearing the axis of which is inclined to the axis of said shaft, of a crank-pin journaled in said cylindrical bearing and having a head, a looper, a looper-carrier pivoted to said crank-pin head on an axis transverse to the longitudinal axis of said crank-pin, and a universally tiltable bearing slidably supporting said looper-carrier at a point spaced from said crank-pin head.

2. In looper mechanism for sewing machines, the combination with a rotary shaft and shaft-head formed with a hollow cylindrical bearing the axis of which is inclined to the axis of said shaft, of a crank-pin journaled in said cylindrical bearing and having a head, a looper, a looper-carrier pivoted to said crank-pin head on an axis transverse to the longitudinal axis of said crank-pin, a universally tiltable bearing slidably supporting said looper-carrier at a point spaced from said crank-pin head, and means whereby the working position of said crank-pin in said cylindrical bearing may be shifted axially of the latter.

3. The combination with a rotary shaft and shaft-head having a cylindrical bearing inclined to the axis of said shaft, of a crank-pin journaled in said bearing, a looper, a looper-carrier bar pivoted at one end to said crank-pin on an axis transverse to the longitudinal axis of said crank-pin, and a universally tiltable bearing slidably supporting the other end of said bar.

4. In looper mechanism for sewing machines, the combination with a rotary shaft and shaft-head formed with a hollow cylindrical bearing the axis of which is inclined to the axis of said shaft, of a crank-pin journaled in said cylindrical bearing and having a head, a looper, a looper-carrier pivoted to said crank-pin head on an axis transverse to the longitudinal axis of said crank-pin, a bearing support, a universally tiltable bearing carried by said support and slidably supporting said looper-carrier, and means whereby said bearing support may be shifted relative to said shaft-head.

5. In a sewing machine, a looper, a carrier on which said looper is fixedly mounted, a universally tiltable bearing in which said carrier is rockably and endwise slidably supported, a crank-pin to which said carrier is pivotally connected on an axis transverse to the longitudinal axis of said crank-pin, and a rotary drive-shaft having a head formed with a hollow cylindrical bearing in which said crank-pin is journaled, said bearing having its longitudinal axis inclined to the axis of revolution of said drive-shaft.

6. In looper mechanism for sewing machines, the combination with a rotary shaft and shaft-head formed with a hollow cylindrical bearing the axis of which is inclined to the axis of said shaft, of a crank-pin journaled in said cylindrical bearing and having a head, a looper, a looper-carrier pivoted to said crank-pin head on an axis transverse to the longitudinal axis of said crank-pin, a universally tiltable bearing slidably supporting said looper-carrier at a point spaced from said crank-pin head, and means whereby the axis of the pivotal connection between the head of said crank-pin and said looper-carrier may be shifted to vary its distance from the axis of said rotary shaft and thus vary the amplitude of the sidewise or needle-avoiding motion of the looper.

7. In looper mechanism for sewing machines, the combination with a rotary shaft and shaft-head formed with a hollow cylindrical bearing the axis of which is inclined to the axis of said shaft, of a crank-pin journaled in said cylindrical bearing and having a head, a looper, a looper-carrier pivoted to said crank-pin head on an axis transverse to the longitudinal axis of said crank-pin, a universally tiltable bearing slidably supporting said looper-carrier at a point spaced from said crank-pin head, and means to prevent said crank-pin from moving endwise in and relative to said cylindrical bearing.

8. In looper mechanism for sewing machines, the combination with a rotary shaft and shaft-head formed with a hollow cylindrical bearing the axis of which is inclined to the axis of said shaft, of a crank-pin journaled in said cylindrical bearing and having a head, a looper, a looper-carrier pivoted to said crank-pin head on an axis transverse to the longitudinal axis of said crank-pin, a universally tiltable bearing slidably supporting said looper-carrier at a point spaced from said crank-pin head, and a collar fixed to said crank-pin and coacting with said shaft-head to prevent endwise movement of said crank-pin in and relative to said cylindrical bearing.

ALBERT H. DE VOE.
